(57) **CLAIM**

The ornamental design for a connectable beverage bottle, as shown and described.

DESCRIPTION

FIG. 1 is a top front left side perspective view of a connectable beverage bottle showing my new design;

FIG. 2 is a top rear right side perspective view thereof;

FIG. 3 is a bottom front left side perspective view thereof;

FIG. 4 is a bottom rear right side perspective view thereof;

FIG. 5 is a left side view thereof;

FIG. 6 is a right side view thereof;

FIG. 7 is a front view thereof;

FIG. 8 is a rear view thereof;

FIG. 9 is a top view thereof;

FIG. 10 is a bottom view thereof;

FIG. 11 is a cross-sectional view thereof taken along section 11-11 of FIG. 9;

FIG. 12 is a cross-sectional view thereof taken along section 12-12 of FIG. 9;

FIG. 13 is a cross-sectional view thereof taken along section 13-13 of FIG. 7;

FIG. 14 is a cross-sectional view thereof taken along section 14-14 of FIG. 9;

FIG. 15 is a cross-sectional view thereof taken along section 15-15 of FIG. 9; and,

FIG. 16 is an environment top front left side perspective view thereof, showing the connectable beverage bottle in a connected configuration.

The broken lines show unclaimed portions of the connectable beverage bottle only and form no part of the claimed design.

(Continued)

In the drawings, the dash-dot-dash broken lines represent sectional designations that form no part of the claim.
